UNITED STATES PATENT OFFICE.

MAX STEWIEN, OF CHARLOTTENBURG, NEAR BERLIN, GERMANY.

MEANS FOR PHOTOGRAPHICALLY REPRODUCING PRINTED MATTER.

Application filed August 30, 1921. Serial No. 496,924.

(GRANTED UNDER THE PROVISIONS OF THE ACT OF MARCH 3, 1921, 41 STAT. L., 1313.)

To all whom it may concern:

Be it known that I, MAX STEWIEN, a citizen of the German Republic, and resident of Charlottenburg, near Berlin, Germany, have invented certain new and useful Improvements in and Relating to Means for Photographically Reproducing Printed Matter (for which I have filed applications in Germany March 13, 1914, November 24, 10 1920, and March 1, 1921; in Great Britain January 7, 1921, and in France January 14, 1921), of which the following is a specification.

This invention relates to photographic 15 production of printed matter particularly from text books and has for its purpose to provide a device which is simple in construction and manipulation and which allows quick working.

20 The invention is illustrated on the accompanying drawing wherein

Fig. 1 is a sectional elevation of a reproducing device in accordance with the invention.

25 Fig. 2 shows a film spool and a bearing for same in sectional top view.

Fig. 3 shows lateral views of the film spool of Fig. 2 and of its bearing.

30 Fig. 4 is a transverse section through a winding roller for the exposed film showing the connection of the film with the roller.

Fig. 5 is a sectional elevation of the winding roller with bearing of Fig. 4 having connected thereto a portion of a film.

35 Fig. 6 shows a gripping device for photographs.

Fig. 7 is a section through a guide for the gripping device of Fig. 6 and of a closing strip for the guiding slot.

40 Fig. 8 illustrates a film cutter.

The reproducing device comprises a frame and table for supporting a book and for holding a leaf of same which forms an original to be reproduced in exposing position and a reproduction camera. The frame for supporting the book and for holding its leaves comprises two pillars 1 (of which only one is visible on the drawing) between which a suction surface 2 is held in upright position.

45 Under the suction surface 2 is arranged a rotatable table 3 supported on its lower side by a guide tube with toothed rack 4. The tube 4 is guided in a sleeve 5 and can be moved up and down in the same

by means of a suitable gear. 6 are mercury lamps arranged in front of the suction surface 2. The reproduction camera as a whole is designated 7. It contains a spool 8 for a sensitive film or paper strip and a winding roller 9 for same; 10 is a guide for the film, 11 a gripping arm for samples of exposed film and 12 a film cutter.

The operation of the reproducing device of Fig. 1 is as follows:

A book containing the originals to be reproduced is put on table 3 which is so adjusted in height and in angular position that the inner edge of a leaf to be reproduced just comes below the lower edge of the suction surface. Thereafter suction is started and the leaf is raised so that it is firmly held against the suction surface. This being done an exposure is made and a suitable portion of the film wound on roller 9. For photographing the back side of the leaf, the leaf is turned over and the table rotated for 180°. On again raising the leaf the back side of same comes into exposing position. Exposures may be made in quick succession and the exposed film wound on roller 9.

It is essential for quick working that the mechanism is of simplest form. This requires before all easy insertion of the film spool and a construction whereby an automatic slight braking effect is exercised on the spool securing the film against unintentional unwinding.

To this end the front discs of the film spool which guide the film are provided with two pins 13 having an angular displacement from each other different from 180°. By means of said pins the spool is held in annular grooves 14 of bearing members 15. The two pairs of supporting pins give on withdrawing the film or paper a slight braking effect.

The winding roller 9 is provided with a steel sheet 16 fastened thereto having at its free end a clamping device 17 adapted to clamp the end of the film. 18 is a cut out adapted to receive clamp 17.

In order to allow quick development it is necessary that the several exposures made on the film or paper strip are as far as possible alike. This requires the possibility of a control of the exposed film. To this end rotatable arm 11 with gripping device 19 and handle 20 is provided which allows seiz-

ing and transporting of a piece of film separated from the film by the cutting device. This consists of the above mentioned knife 12 and two further knives positioned transversely to knife 12. The particular form of knife 12 allows to make a cut in the middle part of the film only between knives 21, 22 which are adapted to make longitudinal cuts; on repeatedly operating knife 12 it becomes possible to separate off a piece of the film so as to examine the degree of exposure. 23 is a protecting strip under spring tension secured to the film gripping device 11, 19, 20 and closing the guiding slot irrespective the position of arm 11.

What I claim is:

1. In a device for photographically reproducing printed matter particularly from text books in combination with a reproduction camera, a suction device having a plain suction surface directed toward the objective of the camera, a table forming a support for the original to be reproduced, and means for adjusting the height of said table independent from the camera.
2. In a device for photographically reproducing printed matter particularly from text books in combination with a reproduction camera a frame comprising a rotatable table forming a support for the originals to be reproduced and a suction chamber provided with a plain perforated suction surface above said table in such relation to the table and to the camera that opposite sides of

leaves of a book placed on the table can be brought in succession to engagement with the suction surface by turning and suitably adjusting the rotatable table and reproduced in that position.

3. In a reproduction camera particularly for reproducing printed matter from text books a film spool, a film transporting lever rotatably mounted in the camera casing provided with gripping devices adapted to be operated from outside the casing, the lever movable within a slot of the casing and connected with ribbons under spring tension for keeping the slot in the casing tightly closed irrespective the position of the lever.

4. In a reproduction camera particularly for reproducing printed matter from text books a film spool for a sensitized strip a further spool for unwinding the film from said first named spool, a film transporting lever, a cutting device adapted to cut out pieces without dividing the film, the cutting device and the film transporting lever so cooperating with each other that film pieces can be seized by the film transporting lever and removed from the film.

In testimony whereof I have signed this specification in the presence of two subscribing witnesses.

MAX STEWIEN.
